W. H. WIX

NAME PLATE

Filed Dec. 17, 1924

Inventor
William H. Wix.
By E. Watson Brewington.

Attorney

UNITED STATES PATENT OFFICE.

WILLIAM H. WIX, OF BALTIMORE, MARYLAND.

NAME PLATE.

Application filed December 17, 1924. Serial No. 756,437.

To all whom it may concern:

Be it known that I, WILLIAM H. WIX, a citizen of the United States, residing at Baltimore city, State of Maryland, have invented certain new and useful Improvements in Name Plates, of which the following is a specification.

This invention relates to signs.

It is a well known fact that almost all houses now built are equipped with plumbing or heating apparatus employing pipes. It is also well understood that most of such apparatus, as installed in the modern dwelling, is installed without definite construction plans and that, even when the owner possesses such definite installation data it is difficult to obtain the service of the person, firm, company or corporation which did the installation, because of difficulty in finding out who made the same.

The object of the invention is to provide a name plate which may be attached to any such installation by the person making the same and it will indicate to the owner, in the event of repairs being necessary, to whom he should apply for such repairs.

To this end the invention contemplates the provision of a name plate indicating that the installation was put in place by a particular party, the name plate being of such character that it may be readily attached to any pipe leading from the heater or connected with the plumbing.

The most important object of the invention is therefore to provide a particular form of name plate capable of being attached to any pipe around a heating or plumbing plant, the plate being adapted to be secured to such pipe in a manner that will display the name of the person who made the installation.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a face view of the device as applied to a pipe.

Figure 2 is a figure on the line 2—2 of Figure 1.

Figure 3 is a side view of the device.

Figure 4 is a view similar to Figure 2 showing a modification employing serrations.

The invention, in its present embodiment, consists of a disc 10, whereon is cast or otherwise indicated a legend 11 showing by whom the installation was effected. Preferably, for purposes of preventing wear, this disc is surrounded by an upstanding rim 12. Centrally disposed of the disc is an orifice 13 wherethrough projects a bolt 14.

On the back or rear side of this disc is a pair of spaced lugs 15 having angular notches 16' so that the disc may be positioned on a pipe. These notches may either be plain in surface as shown in Figure 2 or serrated as shown in Figure 4. Through the orifice 13 extends the bolt 14 and this bolt passes through the center of a securing band 16, the band being of flexible material so that it may be bent around the pipe P, thus enabling the device to be secured by suitable means such as the bolt 17, and is preferably perforated at 18 for the purpose of adjustment.

It will be obvious that other securing devices may be employed but it will be noted that the essentials of the invention are the employment of a name plate, the lugs 15 and a suitable securing band located between said lugs.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

The combination with a name plate; of lugs projecting rearwardly from said name

plate, each formed integrally therewith and positioned to hold said name plate in vertical alinement with the pipe to which the plate is to be attached and a flexible securing band pivotally attached to said plate between said lugs on the rear side thereof, each of said lugs having its rearward edge

notched to engage the pipe, the edge of the notched portions of said lugs being serrated, and means to adjustably connect the ends of ¹⁰ said securing band.

In testimony whereof I affix my signature.

WILLIAM H. WIX.
